UNITED STATES PATENT OFFICE.

MAHLON E. LAYNE, OF HOUSTON, TEXAS.

PUMP MECHANISM.

1,272,681.

Specification of Letters Patent. Patented July 16, 1918.

Application filed July 19, 1916. Serial No. 110,012.

To all whom it may concern:

Be it known that I, MAHLON E. LAYNE, a citizen of the United States, residing at Houston, in the county of Harris and State 5 of Texas, have invented certain new and useful Improvements in Pump Mechanism, of which the following is a specification.

This invention relates to well pumps, and has reference particularly to pumps and to 10 the means for lubricating and protecting the same. The principal objects of my invention are: the provision of an improved means for lubricating the pump; the provision of means for equalizing pressure conditions on and about the various bearings in order to prevent water passing through 15 the bearings; and the provision of means whereby the bearings are protected from sand and other foreign substances.

20 The foregoing, together with such other objects as may hereinafter appear or are incident to my invention, I attain by means of a construction, certain embodiments of which I have shown in the accompanying drawings, wherein—

25 Figure 1 is a sectional view taken through a well and showing the general arrangement of the pumping apparatus therein; Fig. 2 is an enlarged side elevation of a multi-stage 30 pump such as shown in Fig. 1; Fig. 3 is a vertical section taken through the pump; Fig. 4 is a sectional view of one of the novel features of my invention; Fig. 5 is an enlarged showing of certain of the details of 35 the pump; Fig. 6 illustrates a modification of the structure of Fig. 3; and Fig. 7 is a partial vertical section through a modified form of pump embodying my invention.

40 Referring to Fig. 1, it will be seen that I have therein shown a deep well pump apparatus, the pit of the well being designated by the numeral 7, the well casing by the numeral 8, the lower portion 9 of the casing being perforated in the water bearing strata. 45 Suspended from the framing 10 is the discharge casing 11, which is comprised of a plurality of sections suitably joined together. The pump proper, which is of the multi-stage type, is indicated by the letter A, a portion of the pump being shown on an enlarged scale in Fig. 3. From inspection of 50 this figure and also of Fig. 2, it will be noted that the pump casing is secured to the discharge casing 11 by means of a neck casting 12. The pump comprises the pump runners or impellers 15, keyed to the stub shaft 17;

the pump stock castings 14, which are provided with discharge passages, and between which the runners or impellers 15 are located; and the tubing 13 which connects the 60 castings. Certain of the stages are suitably spaced apart by providing one or more of the castings 14 with a long neck 16, or by some other form of spacing means. The discharge passages connecting these stages are 65 formed in the parts 14, 16, and 15^a, the last preferably being an extension of the runners 15, next above. This extension 15^a depends within the neck 16 and rests upon the top of the corresponding casting 14, the lower edge 70 being notched to provide the passages 19 for the purpose hereinafter stated.

In order to properly maintain the alignment of the stub shaft during operation, I provide a bushing 18 which has an outside 75 bearing on the extension 15^a and is threaded into the stationary casting 14 of which the neck 16 forms a part. The bearing is lubricated by means of a pipe 20 leading from the surface of the ground and connected as 80 indicated in Fig. 3 to the passage 21 in the bushing, a space being provided above the upper end of the bushing so that the oil may penetrate both to the inside and outside surfaces of the bushing. The runner 15 above 85 the bushing preferably fits the shaft, with such tightness that no leakage can occur upward between the runner and the shaft. The lower end of the bushing is provided with a series of passages 22 (Fig. 5) so that substantially the same water pressure is applied 90 to the bearing surface between the bushing and the shaft and the bearing surface between the bushing and the extension or housing 15^a. 95

The purpose of this arrangement is to equalize the pressure at the bearing surfaces inside and outside the bushing. With a centrifugal pump there is a tendency to produce a slight suction at the point marked 100 15^b (Fig. 3) between the lower surface of the casing member 14 and the upper surface of the runner 15, while in the passage between the runners or impellers and opposite the passages 19, there is a substantial pressure so that if the passages 22 were not provided there would be a tendency of the water 105 to flow in at the passages 19 upward between the outer surface of the bushing and the inner surface of the extension or housing 15^a, and then downward along the shaft. 110 This circulation would necessarily carry in

sand and other foreign substance tending to cut out the bearings. The provision of the passages 22 eliminates this circulation since the pressures at the two bearing surfaces of the bushing are equalized. The inflow of oil through the passage 22 and to the bearing surfaces of the bushing also tends to keep out the water and foreign substances.

10 The bushing also serves to protect the bearing surface between the casing member 14 and the shaft 17 which turns in such casing member. Heretofore the casing member and shaft have worn rapidly at this point because of the exposure to sand and water and because of the circulation tendency along the shaft heretofore referred to. The provision of the bushing not only blocks this circulation, but protects the bearing in the casing member 14 in another way, and due to the fact that the bushing 18 assumes the work of supporting the shaft. The bearing work between the shaft and casing member 14 is therefore reduced to a minimum and the wear correspondingly reduced.

It will of course be understood that this bushing construction may be used in pumps having any number of impellers and having any number of stages with the proper number of bearings, the construction of Fig. 3 and those of Figs. 6 and 7 being merely illustrative of a number of the applications of the invention which is of broad scope, as will be apparent by reference to the claims. My invention also contemplates the use of the construction, where feasible, in other relations aside from pump constructions.

The manner of supporting the length of the pipe 20 is shown in Fig. 4, in which figure is also shown the arrangement of the pump shaft 17^a, the bottom section of which is the stub or runner shaft 17. The pump shaft comprises a plurality of sections, connected by threaded collars 23, which are supported on bearing blocks 24 arranged at corresponding intervals. The blocks 24 are supported in the jointed shaft casing 25. The shaft casing excludes the water and sand during operation and thereby protects the shafting and bearings; it serves as a support for the bearings, thereby preventing whipping of the line shaft; and it serves as a means for lubricating the bearings, the oil being admitted at the top through the pipe 26, and working down from bearing to bearing to the pump neck.

Fig. 6 illustrates a modification of the invention wherein the housing member 27, corresponding to the extension or housing 15^a, is made separate from the runner 28 immediately above. The housing is of course keyed to the shaft 29 so that it turns with it, and the function accomplished is the same as in the construction of Fig. 3, the latter construction being preferred be-

cause it is a simpler and more desirable construction to make the runner 15 and extension 15^a in one piece. The bushing 30 is just the same in construction as the bushing 18 of Fig. 3, and has its lower end screw-threaded into the casing member 31 as in the other form of construction. The construction in other respects being the same as Fig. 3, no further description is necessary.

Fig. 7 illustrates the application of the invention to a different type of pump useful for other purposes and particularly adapted for mine drainage or city water works or other locations where there is room to admit of this structure. The hydraulic load in this type of construction is balanced. Balanced constructions of this general type are old, but my invention as applied thereto is new and my construction eliminates the necessity for using a stuffing box between the stages as has heretofore been the case, my bearing construction acting as a stuffing box. In this construction, 32 is the shaft; 33 the pump casing; 34 is my improved bearing or bushing which is secured rigidly in position in the casing 33; 35 and 36 are the runners or impellers keyed to the pump shaft 32 below the bearing 34; 37 and 38 are the runners secured to the shaft 32 above the bearing 34; 39 is the passage leading from the lower set of impellers to the upper set of impellers; 40 is the discharge passage leading from the impellers 38; and 41 is the oil supply pipe which leads to the passage 42 in the bearing 34. The runners 38 are provided with the extension or housing 43 bearing upon the outer surface of the bushing or bearing 34, and the pressure on the inner and outer surfaces of the bushing or bearing 34 are equalized by means of the passages 44 corresponding to the passages 22 in the construction of Fig. 3. It will be seen that the function and utility of the construction as applied to this type of pump is the same as that in the construction of Fig. 3, and that the bushing or bearing acts as a stuffing box between the upper and lower sections of the pump. The arrows indicate the path of the water through the pump without further description. It will be understood that this and other pump constructions embodying the invention may be used in horizontal or positions other than the vertical positions illustrated, if desired, without departing from the invention, that the lubricating feature of the invention, while important is secondary to the protection feature, and that the invention is not avoided by omitting the lubrication even though the utility is considerably lessened.

I claim:

1. The combination in a centrifugal pump having a plurality of stages, of a bearing for the driving shaft of the pump located between stages, said bearing being provided

with means for substantially equalizing the pressure on the inside and outside of said bearing.

2. The combination in a centrifugal pump having a plurality of stages, of a casing member between stages, a driving shaft, a bearing for the driving shaft carried in said casing member and extending within the rotating part of one of the stages and means for balancing pressure conditions around said bearing.

3. The combination in a centrifugal pump, of a pair of impellers, a casing member located therebetween, a driving shaft for 15 said impellers extending through the casing member, a bushing mounted in said casing member and providing a bearing for the shaft and a bearing for one of the impellers, and means for balancing pressure 20 conditions around said bushing.

4. The combination in a centrifugal pump, of a pair of impellers, a casing member therebetween, a driving shaft for said casing member providing a bearing for the 25 driving shaft and extending within one of the impellers, and means for introducing a lubricant at the end of the bushing lying in the impeller.

5. The combination in a centrifugal pump 30 having a plurality of stages, of a driving shaft, a relatively fixed casing between the stages, a bearing for said shaft mounted in said casing and extending within the rotating part of one of the stages, means for introducing lubricant to the end of the bearing lying in said rotating part, and means 35 giving access of substantially the same water pressure in the pump to the inner and

outer surfaces of the bearing at a point remote from the end of the bearing in the 40 said rotating part.

6. The combination in a centrifugal pump having a plurality of stages and impellers spaced apart, a driving shaft carrying the impellers, a relatively fixed casing between 45 the impellers, a bushing mounted at one end in the casing and surrounding the shaft, a housing member mounted to rotate with the shaft and fitting over the free end of the bushing, and means giving access of substantially 50 the same water pressure in the pump to the inner and outer bearing surfaces of the bushing.

7. The combination in a centrifugal pump having a plurality of stages and impellers 55 spaced apart, a driving shaft carrying the impellers, a relatively fixed casing between the impellers, a bushing mounted at one end in the casing and surrounding the shaft, a housing member mounted to rotate with 60 the shaft and fitting over the free end of the bushing, and means whereby the water pressure on the inner and outer surfaces of the bushing are balanced, thereby preventing a circulation of fluid along the said 65 surfaces.

8. In a centrifugal pump the combination of a pump casing, a rotary shaft mounted therein and provided with one or more impellers, a bearing for the shaft adjacent the 70 impeller element having an end open and provided with means for equalizing pressure on the outside and inside of said bearing.

MAHLON E. LAYNE.
